UNITED STATES PATENT OFFICE

OTTO ABERLE, OF TUTTLINGEN, GERMANY

HAND BRUSH

Application filed March 9, 1929, Serial No. 345,755, and in Germany February 1, 1928.

The present invention relates to improvements in handbrushes, which with respect to the brushes of known construction offers the advantage of facilitating especially the cleaning of the fingers.

The handbrushes hitherto known consist of a single brush provided at one or two sides with bristles and shaped so as to render the thorough cleaning of the fingers from all sides a difficult task. According to the present invention the cleaning process is materially facilitated by providing two single brushes which by a suitable connection, such as a hinge, can be moved in such a position that the bristles of one brush are directed against the bristles of the other brush. In the open position it is possible to clean the surfaces of the hand. As the hinge is in the form of a link it is possible to clean all sides of the fingers, the link being inclined more or less to adjust the brushes to the size and thickness of the fingers.

The invention is illustrated on the drawing which shows one form thereof.

Figs. 1 and 2 show the two different ways of using the brush.

Fig. 3 is a top view of the brush.

Fig. 4 is a longitudinal section through the brush in open position.

Fig. 5 is a front view of the brush in the position for cleaning the fingers.

The handbrush of the present invention consists of the two single brushes *a* and *b*, hinged together so that they may be used as seen in Fig. 1 for cleaning the surface of the hand and fingers or as shown in Figs. 2 and 5 against the brushes of the other brush for cleaning the individual fingers.

A link *c* serves as a hinge being pivotally connected with the brushes *a* and *b* by means of pins *d*. The use of a link as a hinge renders it possible that the two brushes *a* and *b* when used for cleaning the fingers may be adjusted into certain variable positions by more or less inclining the link *c*, as the size of the fingers vary. The link *c* allows the brushes to be positioned back to back as in Fig. 1 in which position the brushes may be used for cleaning the surface of the hand and fingers.

On the bristle sides the brushes *a* and *b* are formed in the shape of a trough. One trough for instance that of the brush *b* is curved to a greater extent than the other so that it can be more suitable for cleaning the surface of the hand. The brush *b* with the greater curved trough is tapered as shown in Fig. 3 in the direction toward the hinge following the usual form of the fingers.

What I claim is:

1. A handbrush comprising a pair of brushes, each having a concave surface in which bristles are secured, the surface of one brush having a greater radius of curvature than the surface of the other; and a hinge joint securing the ends of the brushes so that they may be folded together in closed position with the concave surfaces facing each other.

2. A handbrush comprising a pair of brushes, each having a concave surface in which bristles are secured, the surface of one brush having a greater radius of curvature than the surface of the other, the surface of one brush being tapered relative to the length thereof; and a hinge joint securing the ends of the brushes so that they may be folded back to back or together in closed position.

In testimony whereof I affix my signature.
